UNITED STATES PATENT OFFICE

HUGO REICHEL, OF CHICAGO, ILLINOIS

SHINGLE-STRIP MACHINE

Application filed November 8, 1926. Serial No. 146,961.

My invention relates to a shingle strip machine for cutting a web of prepared roofing material into longitudinal strips having lateral projections and indentations which, when 5 laid in overlapping courses, have their exposed portions simulating the appearance of individual shingle construction.

My invention provides a machine which is adapted for construction to provide shingle strips of any desired configuration, and one of the objects of the invention is to provide a machine of the class described having novel means for mounting the cutting knives thereon, whereby the knives are easily removed for 15 sharpening or renewal.

It is found in practice that in cutting a web of the material into strips, some of the strips are not entirely severed and it is another object of the invention to provide novel, economical and effective means for accomplishing the complete severance of such strips as have not been entirely severed in the cutting operation.

Other further and more specific objects will 25 become apparent from consideration of the specification and drawings wherein:

Fig. 1 is a side elevation of the machine showing the power drive and connecting gears;

Fig. 2 is a sectional view taken along line 2—2;

Figs. 3 and 4 are fragmentary plan views of the cutter head drawn to a larger scale;

Fig. 5 is a sectional view of the cutter head taken along the line 5—5;

Figs. 6, 7, 8 and 9 are detail views taken along the lines 6—6, 7—7, 8—8 and 9—9;

Figs. 10 and 11 are plan and end views, respectively of the cutter head;

Fig. 12 is a plan view of a material strip, showing the cutting lines resulting from feeding the material strip between a pressure roller and the cutter head; and

Fig. 13 is a view along the line 13—13 showing a typical section of a bearing box.

Referring to the drawings, the machine comprises a supporting frame 11, upon which are mounted the feed rollers, pressure rollers, cutter heads and driving gears. A pair of 50 standards 12 positioned at a convenient dis-

tance from the frame 11, provides a support for a series of rollers operating for a purpose to be hereinafter more fully explained.

Upon the front of the frame 11, is mounted a pair of standards 13, which furnishes a 55 mounting for a pair of feed rollers 14 and 15 between which a fabric sheet 16 is to be fed. The rollers 14 and 15 are adjustable relative to each other by threading the nuts 17 and 18 on and off the bolts 19. The bolt 19 is mounted at its lower end in a box 20 which is 60 slideable between the arms 40 forming the upper portion of the standards 13. The arms 40 form a guideway in which the box 20 moves when the nuts 17 and 18 are turned on and off 65 the bolts 19. The construction of the guideway is best shown in Fig. 13.

Pairs of standards 21 and 22 are shown at the top of the supporting frame 11 to provide supports and guideways for a cutter 70 head 23 overlying a roller 24 and a cutter head 25 overlying a roller 26 respectively. A pair of standards 27 is likewise provided as supports for feed rollers 28 29. The cutter heads 23 and 25 and the feed roller 28 are 75 adjustably mounted in their respective pairs of standards by nuts 17 18 bolts 19 and boxes 20 similar to the mounting provided for the feed roller 14.

The rollers and cutter heads are actuated 80 by a series of gears and a chain drive from a motor (not shown), so as to move the fabric to the right as shown in Fig. 1. The power is applied to the gear 30 so as to rotate it in an anti-clockwise direction. The gear 30 meshes 85 with a relatively large gear 31 which is fixedly mounted on the roller 24 to actuate the same in a clockwise direction. A sprocket 32 mounted on the roller 24 and a chain drive 33 actuate a sprocket 34 on the roller 15 so as to rotate the roller 15 in a clockwise direction. A gear 35 is fixedly mounted on the roller 24 and meshes with an idler 36 which in turn meshes with a gear 37 the latter being fixedly fastened on the roller 26. The gear 37 meshes 90 with an idler 38 which in turn meshes with a gear 39, the latter being fastened on the roller 29. Each of the rollers 15, 24, 26 and 29 are thus rotated in a clockwise direction. A gear 51 on the roller 15 meshes with a gear 100

52 on the upper roller 14 and likewise the gears 35, 37 and 39 mesh with corresponding gears 41, 42 and 43 respectively on the cutter heads 23 and 25 and the roller 28, respectively. By this arrangement of the gears which are shown diagrammatically only it is obvious that the rollers 14 and 28 and the cutter heads 23 and 25 respectively rotate in an anti-clockwise direction as viewed in

10 Fig. 1.

10 The cutter head 25 is shown as of smaller diameter than is the cutter head 23. Only one of the cutter heads is maintained in operative position at any one time, use being 15 made of the nuts 17 and 18 and the bolt 19 for the purpose of moving the cutter heads into or out of their operative position. It is thus possible to cut the web of material into strips of different sizes as desired by merely throwing 20 the cutter heads in or out of gear as shown or by substituting heads of smaller or larger diameter than those shown in the machine.

15 In Figs. 10 and 12, are shown a typical cutter head 23 and a portion of a web of fabric 25 16 respectively, after the web has been run between the cutter head and its cooperating roller. The web is shown as cut into six longitudinal strips and each of the strips as 30 cut transversely at regular intervals to form relatively short strips 45. The width of the strips as well as their length depend upon the size of the roller used while their indentations and lateral projections depend upon the arrangement of the knives upon the cutter 35 head.

40 One of the chief features of novelty in the invention lies in the provision of an angular cross-sectioned cutter head which can be easily and economically manufactured by casting 45 and upon which the knives 46 are mounted and fastened to the cutter head by means of bolts 47 and ordinary angle irons 48. The knives and angles include the knives 46^a and angle irons 48^a extending longitudinally of the cutter head, the diagonally extending knives 46^b and angle irons 48^b, and the knives 46^c and the angle irons 48^c. The knives 46 are riveted to the angle irons 48 and for the purpose of easy removal of the knives the 50 angle irons are fastened to one of the faces of the cutter head by means of bolts 47. The knives are of such depth and shape as to have their cutting edges lying in a cylindrical surface concentric with the axis of the cutter 55 head as best shown in Fig. 6. In operation the cutter head and its cooperating roller are so positioned that the surface of the roller is tangential to the cylindrical concentric surface in which the cutting edges of the knives 60 lie. The knives 46^a, 46^b and 46^c are positioned so that they form continuous cutting edges with the result that the fabric is cut as indicated in Fig. 12. By providing a plurality of 65 bolt holes for the bolts 47 the direction of the

knives can be varied at will and resulting projections and indentations likewise varied. The cutter head is shown as hexagonal in cross section but it can be made octagonal or of any other desired angular cross section, which 70 feature by reason of its economy of manufacture and ease of assembly and mounting constitutes one of the highly desirable objects of the invention.

75 The rollers 14' and 15' comprise shafts 53 and 54 upon which a plurality of concave and convex rollers 55 and 56 are respectively mounted. The sheet 16 is fed between these rollers after being cut into longitudinal strips 45 for the purpose of completely severing the lateral edges of the strips. This object is accomplished by reason of the strips being temporarily corrugated longitudinally between the concave and convex rollers as best shown in Fig. 2. Such corrugation of the strips necessarily diminishes their over-all width and requires the separation of the lateral edges of adjacent strips.

80 85 Thus it will be seen that I have provided an economical and novel cutter head and knife mounting and novel means for separating the sections of shingle strips.

90 I claim:

95 1. In a shingle strip machine, the combination with means for severing a sheet of material into a plurality of generally longitudinal strips, of means for separating the contiguous edges of adjacent strips, said separating means comprising corrugating rolls through which said strips are fed to corrugate the strips longitudinally.

100 105 2. In a shingle strip machine, the combination with means for severing a sheet of material into a plurality of generally longitudinal strips, of means for breaking any final adhesion of the adjacent edges of such strips said breaking means comprising a plurality of pairs of concavo-convex rollers between which the individual longitudinal strips are fed.

110 In testimony whereof I have affixed my signature.

HUGO REICHEL.
